UNITED STATES PATENT OFFICE

RASMUS R. HELLVIK, OF NEW YORK, N. Y., ASSIGNOR TO SOLOMON KRAMER, OF NEW YORK, N. Y.

DESIGN FOR A WALL BRACKET

Application filed March 14, 1929. Serial No. 30,466. Term of patent 3½ years.

To all whom it may concern:

Be it known that I, RASMUS R. HELLVIK, a citizen of Norway, and resident of New York city, New York, have invented a certain new, original, and ornamental Design for a Wall Bracket, of which the following is a specification, reference being had to the accompanying drawing, forming part thereof.

The figure of the drawing is a front view of a bracket showing my new design.

I claim:

The ornamental design for a wall bracket substantially as shown.

RASMUS R. HELLVIK.
